UNITED STATES PATENT OFFICE.

BERNARD FAYMONVILLE, JR., OF BRIDGEPORT, CONNECTICUT, ASSIGNOR OF TWENTY-FOUR ONE-HUNDREDTHS TO FRANCIS GERALD LEE AND TWENTY-FIVE ONE-HUNDREDTHS TO THEODORE BERTRAND FORDHAM, BOTH OF BRIDGEPORT, CONNECTICUT.

RAILWAY-SWITCH.

1,242,671.

Specification of Letters Patent.

Patented Oct. 9, 1917.

Application filed March 28, 1917. Serial No. 157,947.

To all whom it may concern:

Be it known that I, BERNARD FAYMONVILLE, Jr., a citizen of the United States, and a resident of Bridgeport, in the county of 5 Fairfield and State of Connecticut, have invented a new and Improved Railway-Switch, of which the following is a full, clear, and exact description.

This invention relates to railway switches 10 and particularly to an automatically operated switch, which switch may be operated by trains traveling in either direction, and has for an object the provision of means accomplishing the results mentioned by the 15 manipulation of a shoe or other means by the engineer when he desires an operation of the switch.

Another object in view is to provide a switch which may be operated from the 20 main line by a contact shoe on the engine or by a contact shoe on the engine positioned on the branch line.

A still further object of the invention is to provide an automatically actuated switch 25 which is always locked in one position but which is unlocked when the mechanism is operated immediately previous to the shifting of the switch points.

In the accompanying drawings:

30 Figure 1 is a top plan view of the principal parts of a switch and operating mechanism embodying the present invention.

Fig. 2 is a top plan view of a section of 35 track and the remaining part of the mechanism shown in Fig. 1.

Fig. 3 is a transverse sectional view through Fig. 1 on line 3—3, the same being on an enlarged scale.

Fig. 4 is a view similar to Fig. 3 but showing the parts in a different position.

Fig. 5 is an enlarged detail perspective view of the casing and associated parts holding the switch shifting and locking means.

45 Fig. 6 is a detail perspective transverse section through Fig. 1 on line 6—6.

Fig. 7 is a detail fragmentary sectional view through Fig. 1 on line 7—7.

Fig. 8 is an elevation of part of a switch 50 embodying certain features of the invention, said elevation being taken through line 8—8 of Fig. 1.

Fig. 9 is an elevation of part of a switch

embodying the invention, said elevation being taken on line 9—9 of Fig. 1.

Fig. 10 is an elevation of part of a switch 55 embodying the invention, said elevation being taken on line 10—10 of Fig. 2.

Referring to the accompanying drawings by numerals, 1 indicates the rails of the 60 main line and 2 the rails of the side line. Figs. 1 and 2 show the immediate vicinity of a switch together with the switch mechanism, the structure shown in Fig. 2 being positioned below Fig. 1 merely on account of 65 the limitation of the drawings but properly belongs at the right. When a train is approaching the switch from the right it will first reach the vicinity of the switch after passing point 3, and if the shoe on the engine is lowered it will strike the operating rail 4 and depress the same for operating the mechanism hereinafter fully described. The shoe of the engine may be of any kind 70 put preferably of some kind which may be 75 easily raised and lowered so that when it is raised the engine will pass the switch without operating the switch mechanism but when lowered it will operate the switch mechanism so that a train may be switched 80 off to the rails 2 of the side line. When the shoe strikes the operating rail 4 the same moves downwardly on its pivotal mounting 5 and as it moves it compresses the spring 6 (Fig. 10) and moves the bell-crank lever or 85 system of cranks and shafts 7.

As shown in Fig. 2, the cranks and shafts or bell-crank lever structure 7 is operated so that the crank arm 8 is moved downwardly pivotally and the crank arm 9 is 90 moved or swung in a vertical plane so as to pull the rod 10 longitudinally in respect to the track. The pulling of the rod 10 operates the bell-crank lever 11 (Fig. 1) against the action of spring 12, said bell-crank lever being pivotally mounted at 13 in a casing 14. The free end of the lever 11 fits into the slot 15 of a sliding block 16 (Figs. 3 and 4) so that when bell-crank lever 11 is moved by a pull on rod 10 the end of the 100 lever will engage the sliding block 16 and move the sliding block against the action of spring 17. The sliding block 16 is guided by the bars 18 and 19 by reason of the fact that the rod 20 extends through the bracket 105 21 of casing 14 and the fact that the sliding

block 16 has a pair of upright spurs 22 straddling the bar 18. Rod 20 is a switch rod and is either rigidly or pivotally connected, as desired, to the switch points 23 and 24, whereby when the parts are moved to the position shown in Fig. 4 the switch will be opened and the train from the main line 1 will be switched on to the side line 2.

The rail 4 is made of such a length as to be sufficiently near the flange operated rail 25 so that the flange of one of the wheels of the engine will strike the rail 25 before the shoe on the engine will leave rail 4. This is to allow the operation of means hereinafter described which will maintain the switch open until the entire train has moved on to the side line 2. When the rail 25 has been depressed the flanged rail 26 will also be depressed and one of these rails will be continually engaged by one of the wheels of the train until the last car has completely cleared the switch. When the rail 25 has been engaged by the flange of one of the wheels of the engine it will be moved downwardly as shown in dotted lines in Fig. 9, whereupon the crank members 27 and 28 will be swung to a certain extent and the shafts 29 and 30 will be rocked. Shaft 29 is merely a sub-shaft for providing a pivotal connection and thereby cause the rail 25 to remain in a horizontal position, but the shaft 30 extends vertically, as shown in Fig. 1, and is journaled in a bracket 32. An arm 33 is connected rigidly with shaft 30 and pivotally connected with the link 34 so that when the shaft 30 rocks link 34 will be given a push and the swinging bar 31 will be moved pivotally in a horizontal plane. The link 34 and also links 35 and 36 are connected with bar 31 by suitable bolts or other means extending through the slots 37 and 38, said slots being provided so as to allow a proper adjustment of the parts, though an ordinary round aperture will be sufficient.

When the bar 34 is given a shove links 35 and 36 will be given a pull, link 36 operating the bell-crank lever 39 while link 35 operates an arm 40, which arm is rigidly secured to shaft 41. Shaft 41 is mounted in a suitable bearing 42 (Fig. 9) and the shaft is rigidly secured to arm 43 pivotally connected at 44 to the rail 26. An idle pivotally mounted arm 45 is also provided, as shown in Fig. 9, for maintaining the rail 26 parallel. By this means, when the rail 25 has been depressed motion will be communicated to rail 26 for depressing the same and, consequently, when the last wheel has left rail 25 said rail will remain depressed until the last wheel has passed off the rail 26. A pull on the link 36 as just described will move the bell-crank lever 39 against the action of spring 46 for moving the sliding block 16, the end of one of the arms of bell-

crank lever 39 fitting into slot 15 of the sliding block 16. In connection with the sliding block 16 it will be noted that the spurs or projections 22 not only straddle the rod 18 for guiding the block in its movement but also act as stops in connection with the locking member 47 for locking the switch points in a closed condition, as shown in Fig. 1.

It will be noted that the switch points 75 cannot be moved when the parts are in the position shown in Fig. 1, by reason of the fact that the lock 47 pivotally mounted at 48 will prevent the block 16 from sliding. For this reason the bell-crank levers 11 and 39 strike the curved sides or cams 49 and 50 of the locking member 47 and raise said lock, as shown in Fig. 4, after which the block may be freely moved for opening the switch. In case a train should approach the switch 25 from the side track, the rail 26 will first be depressed and bell-crank lever 39 operated for throwing the switch, whereas if the train approached the switch from the main line bell-crank lever 11 would be operated. As 20 shown in Fig. 10, the rail 4 is returned by spring 6 while the rails 25 and 26 are returned by suitable springs 51 and 52, as shown in Figs. 6 and 7, whereby when the train has passed the switch will automatically resume its closed and locked position. The return of the switch is assisted by the spring 17. In order to prevent an excessive return a substantially U-shaped member 7' is pivotally connected to wire 4 and straddles 100 the supporting bracket 9', said U-shaped member having a slot therein for accommodating the limiting pin 8'.

What I claim is:

1. In a device of the character described, 105 the combination with a switch, of a rod connected to the switch for shifting the same, a sliding block connected with said rod, a spring acting on said sliding block for holding the same and said rod in such a position 110 as to maintain the switch closed, a pivotally mounted locking member engaging said block and locking the same against movement in one direction whereby said switch is locked closed, cams arranged on said 115 locking member, and means for moving said block formed so as to engage said cams and operate the same for disengaging said lock immediately previous to the movement of the block.

2. In a device of the character described, the combination with a switch, of a rod for operating said switch, a sliding block connected with said rod, a pair of bell-crank levers acting on said block for sliding the 125 same and moving said rod for opening the switch, a locking member formed with cams for normally locking the block against movement, said cams being positioned so as to engage the bell-crank levers before the 130

bell-crank levers engage the block, and means operated by a train passing over the switch for moving said bell-crank levers.

3. In a device of the character described, 5 the combination with a switch, of an operating rod connected to said switch for opening and closing the same, a spring acting to operate said rod for closing the switch, a sliding block connected with said rod 10 formed with a slot, said block having a projection, a pivotally mounted locking member engaging said projection and normally preventing a sliding movement of the sliding block, said lock being provided with a 15 pair of curved cam members, a bell-crank lever on each side of said block having one end extending into the slot in the block, and means automatically actuated by trains passing over the switch for moving said bell-crank levers whereby the first movement will cause the bell-crank levers to pass to the bottom of said slot and simultaneously engage said cams for disengaging said lock from said projection and finally move 20 the block so that the switch will be shifted to an open position.
4. In a device of the character described, the combination with a switch, of a rod for opening the switch, a sliding block having 25 a pair of projections connected with said rod, said block having a slot extending therethrough, a pivotally mounted locking member resting on said block and engaging 30 said projections for preventing the movement of the block from operating said rod,
- a cam on each side of said pivotally mounted lock, and a pair of bell-crank levers extending into said slot adapted to first engage said cams and move the same to said block out of the path of movement of said 40 projections and then move the block and rod until the switch has been opened.
5. In a device of the character described, 45 the combination of a switch, of a rod for shifting said switch, a sliding block connected with said rod, said sliding block having a projection on the upper face, a pivotally mounted lock member having cam surfaces, said lock member when it is in lowered position being arranged in back of 50 said stop for locking the block against movement, and means actuated by the wheels of a train for engaging said cams and raising said locking member to a position out of engagement with said stop and 55 then moving said rod for shifting said switch.
6. In a device of the character described, 60 the combination of a switch, of a rod for shifting said switch, a block connected with said rod, a spring acting on said block and rod to normally hold the switch in a closed position, a pivotally mounted member having cams engaging said block for normally holding the same closed, and levers actuated 65 by a locomotive engaging said cams for unlocking the block and substantially simultaneously shifting the block and switch connected therewith.
